(57) **CLAIM**

The ornamental design for a bus connector receptacle, as
shown and described.

DESCRIPTION

FIG. 1 is a front perspective view of a bus connector receptacle showing our new design in accordance with one embodiment;

FIG. 2 is a front view thereof;

FIG. 3 is another front perspective view of a bus connector receptacle showing our new design in accordance with the FIG. 1 embodiment;

FIG. 4 is a front view thereof;

FIG. 5 is a top view thereof;

FIG. 6 is back view thereof;

FIG. 7 is a right view thereof, the left view being a mirror image of same;

FIG. 8 is a bottom view thereof; and,

FIG. 9 is a right side sectional view along the line 9-9
illustrated in FIG. 3.

The broken lines in the drawing figures show portions of the
bus connector receptacle which form no part of the claimed
design.

The shade lines in the figures show contour and not surface
ornamentation.
